CLAIM

The ornamental design for a clipboard, as shown and described.

DESCRIPTION

FIG. 1 is a front, top and left side perspective view of a clipboard, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a view in expanded state thereof;

FIG. 9 is a view in expanded state thereof; and,

FIG. 10 is a view in expanded state thereof.

The broken lines shown in the drawings illustrate logo
“xfca” of the clipboard that form no part of the claimed
design.
